Primary Examiner — Ian Simmons*Assistant Examiner* — Keith Frank(74) *Attorney, Agent, or Firm* — Peter Giancana(57) **CLAIM**

The ornamental design for a fragrance bottle with cap, substantially as shown and described.

DESCRIPTION

FIG. 1 is a front perspective view showing our new design for a fragrance bottle with cap;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof; and,

FIG. 7 is a bottom plan view thereof.

In the drawings, features within broken lines form no part of the claimed design.

1 Claim, 3 Drawing Sheets
